UNITED STATES PATENT OFFICE.

WALTER R. MONTGOMERY, OF SHREVEPORT, LOUISIANA, ASSIGNOR OF ONE-HALF TO
WILLIAM B. McCORMACK, OF SHREVEPORT, LOUISIANA.

WHEEL ATTACHMENT.

Application filed March 29, 1923. Serial No. 628,675.

To all whom it may concern:

Be it known that I, WALTER R. MONTGOMERY, a citizen of the United States, residing at Shreveport, in the parish of Caddo and State of Louisiana, have invented a new and useful Wheel Attachment, of which the following is a specification.

This invention relates to an attachment for the wheels of motor vehicles, one of the objects being to provide a simple and compact device adapted to be quickly and firmly attached to a wheel so that by connecting thereto one end of an anchored cable or the like the vehicle can be pulled out of mud holes, sand, etc., under its own power.

Another object is to provide an attachment which will not scar the wheel and which, when not in use, can be stored in a small space.

Another object is to provide a device of this character which can be quickly applied and removed, is formed of but few parts, and will not readily get out of order.

With the foregoing and other objects in view which will appear as the description proceeds, the invention consists of certain novel details of construction and combination of parts which will be hereinafter more fully described and pointed out in the claims, it being understood that various changes may be made in the construction and arrangement of the parts without departing from the spirit of the invention as claimed.

In the accompanying drawings the preferred forms of the invention have been shown.

In said drawings:

Figure 1 is a side elevation of an automobile wheel having the present improvements applied thereto.

Figure 2 is an elevation of the attachment showing the inner side thereof.

Figure 3 is a section on line 3—3 figure 2.

Figure 4 is an enlarged section on line 4—4 Figure 2.

Figure 5 is a view similar to Figure 1 showing a modified construction.

Figure 6 is an enlarged section through the modified structure on line 6—6 Figure 5.

Referring to the figures by characters of reference 1 designates a tubular drum provided, at its outer end, with an annular flange 2 while the inner end of the drum is enlarged annularly as at 3 to provide an

interior recess 4 for the reception of the hub portion of the wheel W. Arms 5, preferably four in number radiate from this enlarged end 3 and as shown particularly in Figure 4 each arm has a longitudinal channel 6 the opposed walls of which are inclined as shown at 7. Each arm also has an opening 8 for the reception of a clamping bolt 9 the threaded stem of which is engaged by a nut 10. That portion of the stem of the bolt nearest the head 11 is angular as shown at 12.

Slidably mounted in each groove or channel 6 is a slide 13 the sides of which are beveled and are adapted to fit snugly against the inclined walls 7 of the grooves or channels 6. Each of these slides have a longitudinal slot 14 and reinforcing ribs 15 are formed along the sides of the slides. The inner ends of the slides are recessed as at 16 thus to clear the hub of the wheel W. The outer end of each slide has an arm 17 extending at right angles therefrom and formed on this arm is a wedge block 18 the converging side faces of which are formed with rounded recesses 19.

Extending from the enlarged portion 3 of drum 1 is a forked lug 20. This lug is adapted to engage the knotted end of a cable 21.

In using this device the bolts 9 are loosened and the slides 13 are moved outwardly so as to allow the blocks 18 to be inserted between certain of the spokes of the wheel. The drum 1 is placed concentric with the hub of the wheel and the blocks 18 are then adjusted toward each other until the adjacent spokes are seated snugly within the recesses 19. The bolts are then tightened by means of the nuts 10 and as the angular portions 12 of the stems are seated in the slots 14 the bolts cannot rotate. Cable 21 is connected to the lug 20 and by then rotating the wheel W the cable will be wound on the drum. As the cable is to be anchored at its outer end this winding thereof will result in the wheel being pulled forward out of the mud hole or the like in which it is embedded.

Instead of providing an attachment such as has been described and which is adjustable to wheels of all sizes, a simplified form can be employed as shown in Figures 5 and 6. In this modified structure which is to be used with one size wheel the radial arms 22

extending from the enlarged end of the drum 23 are formed with radial slots 24 through which are extended bolts 25. Each bolt has a head 26 which merges into the stem of the bolt along curved lines. Thus by placing the bolt between two spokes of a wheel and tightening it by means of a nut 27 the rounded surface of the head will fit snugly against the spokes without marring them. This form of attachment is designed for use primarily on the wheels of the well known "Ford" automobile. It will be noted that a recess 28 is provided at the inner end of the drum for the purpose of receiving the bolt heads and clamp plate of the wheel hub, thereby allowing the arms 22 to rest close to the spokes.

This modified structure is provided with a forked lug 29 similar to the lug 20 and adapted to receive the end of a cable 30.

Attention is called to the fact that the laterally extending arms 17 serve to hold the attachment shown in Figures 1, 2 and 3, laterally away from the wheel so that said attachment will not come against the bolt heads and the clamp plate of the wheel hub.

By providing the drums with the enlarged inner end portions, the cable, while in use, will be held laterally away from the machine so as not to contact with the fender.

The rounded tapered head 26 acts as a wedge when bolt 25 is tightened (see Figure 6) and, because of the peculiar shape of this head the spokes will not be marred.

What is claimed is:

1. An attachment for automobile wheels comprising a drum, cable engaging means extending therefrom, radial arms at one end of the drum, means slidably longitudinally along the arms for wedging between the spokes of a wheel, and means for holding

the slidable means assembled with the arms while sliding thereon and against movement relative to the arms when brought to desired positions.

45

2. An attachment for automobile wheels including a drum, radial arms extending from one end of the drum, there being longitudinal grooves within the arms, slides adjustable within the grooves, means for 50 clamping the slides to the arms, and wedging devices carried by the slides for insertion between the spokes of a wheel.

3. An attachment for automobile wheels including a drum, radial arms extending from one end of the drum, there being longitudinal grooves within the arms having inclined walls, slides adjustable within the grooves and having beveled sides, means for 55 clamping the slides to the arms to bind said beveled sides upon the inclined walls of the grooves, and wedging devices carried by the slides for insertion between the spokes of a wheel, there being opposed spoke receiving recesses within the wedging devices.

65

4. An attachment for automobile wheels including a drum, radial arms extending from one end of the drum, there being longitudinal grooves within the arms, slides adjustable within the grooves, means for 70 clamping the slides in the grooves, arms extending at angles from the slides, and wedging blocks upon the arms having opposed rounded spoke receiving recesses.

75

In testimony that I claim the foregoing as my own, I have hereto affixed my signature in the presence of two witnesses.

WALTER R. MONTGOMERY.
